WINDING MACHINE WITH AUXILIARY DEVICE FOR INITIATING THE WINDING OPERATION

Walter Siegenthaler, Erlenbach, Switzerland, assignor to the firm Schärer- Nussbaumer & Co., Erlenbach, Switzerland

Application August 5, 1938, Serial No. 223,369
In Switzerland October 28, 1937

7 Claims. (Cl. 242—27)

This invention relates to winding machines which are provided with an auxiliary device for initiating the winding operation and in which every time on completion of a winding the full bobbin is removed from the winding position while an empty bobbin is moved into this position.

The present invention comprises improvements in the apparatus disclosed in my U. S. Patent No. 2,131,147.

According to the invention the thread or yarn is wound by means of a stationary guide in a terminal winding during the end period of the winding operation at a point remote from the tip of the bobbin, which is accordingly determined, and is moved during the gyratory movement of the bobbin within the operating range of a gripper member which deflects the yarn laterally by effect of its own movement and thus conveys the thread within the range of a moving thread catch by which it is caught for then being directed onto the next bobbin to be wound.

By this means the production of bobbins of the kind previously described is rendered possible in simple manner, in which the terminal winding is located in more or less close proximity to the tip of the bobbin, that is, spaced apart from the base of the bobbin. This facilitates particularly the unwinding of the end of the thread at the tip of the bobbin as compared with bobbins wound by automatons in which the terminal winding is located at the base of the bobbin and in which the unwinding of the thread at the retaining rings arranged on the base is rendered more difficult and the thread end easily tangles with the base and is then broken.

An embodiment of the invention in the form of a cop winding machine comprising a displaceable and revoluble cop supporting frame is illustrated in the accompanying drawings in which

Fig. 1 is an elevational view showing the position of the cop supporting frame prior to the completion of a winding;

Fig. 2 is a similar view showing the cop supporting frame in a position which it assumes in the end stage of the winding operation;

Fig. 3 is a vertical section on the line III—III in Fig. 2;

Fig. 4 is an elevational view showing the cop supporting frame pushed back into initial position but still rotating;

Fig. 5 is a vertical section on the line V—V in Fig. 4;

Fig. 6 is a view similar to Fig. 4 except that the cop supporting frame is turned further;

Fig. 7 is a vertical section on the line VII—VII in Fig. 6;

Fig. 8 is a vertical section on the line VIII—VIII in Fig. 6;

5 Figs. 9 and 10 each show a different elevation of an example of a driving head of the winding spindle in operative condition;

Figs. 11 and 12 each show a different view of this driving head in inoperative condition, Fig. 12 being a section on the line XII—XII in Fig. 11;

Fig. 12a is a plan view of a cop tube mounted in the driving head of a spindle;

Fig. 13 is a partial elevation of a winding machine provided with such spindle driving heads;

15 Fig. 14 is an elevation of a second example of a spindle driving head;

Figs. 15 and 16 each show a section on the line XV—XV in Fig. 14 and XVI—XVI in Fig. 15 respectively;

20 Figs. 17 and 18 each show a different elevation of a third example of the spindle driving head in operative condition;

Fig. 19 is a front elevation depicting the inoperative condition of this spindle driving head;

25 Figs. 20 and 21 each show a further example of a spindle driving head in operative condition;

Fig. 22 is a section on the line XXII—XXII in Fig. 21; and

Fig. 23 shows a front elevation of this spindle driving head in inoperative condition.

In the example represented by Figs. 1 to 8, the cop supporting frame is provided with two face plates 1, 2 which are interconnected by a hollow shaft 3 by means of which the cop supporting frame is mounted on a fixed bearing shaft 4. The cop supporting frame is advanced step by step longitudinally of the bearing shaft 4 in the direction of the arrow I in Fig. 1 in a manner known per se during the building of the cop with the aid of a feeler (not shown) in dependence of the cop winding under formation. The frame-advancing means is similar to that disclosed in my U. S. Patent No. 2,131,147, wherein it comprises principally the motor driven screw spindle 12 and threaded coupling member 11. The face plate 1 has two projecting arms 1', 1'', which extend in the plane of the plate and serve for alternate cooperation with a longitudinal rail (not shown) arranged in the lower part 5 of the machine frame. Such a rail is shown in my U. S. Patent No. 2,131,147 where it is indicated by reference numeral 13.

The arm of the face plate 1 which extends downwardly cooperates with the longitudinal rail which serves as a stop for this arm, thereby pre-

venting the cop supporting frame from rotational displacement. The face plate 2 is provided, in a manner similar to that described for the face plate 1, with two projecting arms 2', 2'' which extend in the plane of the plate and serve for cooperation with the said longitudinal rail.

On the pair of plates 1, 2 are mounted two winding spindles 6, 6' in diametrically opposed relation, each spindle being constructed as a roller, the roller of the upper winding spindle 6 which assumes the winding position (Figs. 1 to 3) being rotated by bearing engagement with an endless driving belt (not shown) which passes over the same. A driving means comprising endless belt 7 suitable for driving the spindles is shown in my U. S. Patent No. 2,131,147. Each one of the winding spindles 6, 6' is provided at its end projecting beyond the face plate 1 with a driving head 7, 7' respectively provided with an inner elastic and thus resilient holding device 28, 52 (Fig. 12a) for the reception of cop tubes 8, 8' respectively the other ends of which are received in rigid or resilient abutments 9, 9' respectively of a counter holding device 10. The cop tubes can be removed individually from their mounting means by exerting pressure thereon in corresponding manner.

The counter holding device 10 is firmly connected to the face plate 1 by a tube 11 through which passes the bearing shaft 4 and thus forms a component part of the cop supporting frame. In the counter holding device 10 are arranged two hooks 12, 12' which are coordinated to the winding spindles in diametrically opposed relation and serve as temporary stationary guides for the thread. During the operation of the machine the oncoming winding thread A passes over a thread guide 13, which corresponds to thread guide 35 of my Patent No. 2,131,147, and which reciprocates through a certain range corresponding to the length of the conical part of the cop winding in progress of formation, as indicated by the double arrow in Fig. 1.

To each winding spindle 6, 6' is correlated a gripping member in the form of a barbed needle 14, 14' respectively the shanks of which are longitudinally displaceably guided in the face plates 1, 2 and which are loaded by compression springs 15, 15' respectively. As shown in Fig. 1, the barbed needle 14 rests with its smooth end against an abutment 16 fixed to the bearing shaft 4 and projects through a semi-circular recess in the circumference of a disc 17 which recess gives passage to the abutment 16 (Fig. 8). The disc 17 against which the barbed needle 14' abuts with its smooth end, is mounted on the cop supporting frame together with an arm 18, as is evident from Figs. 1 and 2. This arm 18 bears laterally on the lower part 5 of the machine frame by means of its free end. The disc 17 is secured to the hub 18' of arm 18 by any suitable means such as screws 17', and the disc 17 and arm 18 are mounted for relative rotation on a reduced extending bearing portion 3' of shaft 3. The arm 18, which corresponds to arm 10 in my Patent No. 2,131,147, and the disc 17 do not share in the rocking movements which the cop supporting frame performs for the purpose of removing the full cop tubes from the winding position and conveying the empty cop tubes into the winding position.

In feeding the cop supporting frame step by step in the direction of arrow I in Fig. 1 the cop counter holding device 10 approaches the barb of the barbed needle 14 abutting the stationary

abutment 16 more and more. In the final winding phase the oncoming thread slides along the contact hook 12 and passes through the open hook end thereinto, so that, at the corresponding points of the spool the thread is wound in some parallel windings if, after producing the winding proper, the carriage is rotated in order to change the spool at the operative (winding) position, wherein the thread lies in the elbow of the contact hook 12 and the wound spool turns further about its own axis by reason of its inertia, whereby a final winding of parallel threads is produced on the spool.

At the moment of completion of the cop winding proper the projecting arm 1'' of the face plate 1 registers with a notch in a longitudinal rail (not shown) provided in the lower part 5 of the machine frame, whereas the arm 2'' of the face plate 2 registers with a corresponding notch, whereupon the cop supporting frame is rocked round the bearing shaft 4 through half a revolution, preferably automatically (by means not shown), in the direction of the arrow shown in Fig. 3. The means for performing this rocking operation is disclosed in my U. S. Patent No. 2,131,147 where the belt 7 serves to supply the actuating force, and slotted abutment bar 13 limits the rocking movement. Simultaneously with this rocking movement the cop supporting frame is longitudinally displaced relative to the bearing shaft 4 by spring action, whereby it is returned into initial position. The means for performing this longitudinal return movement is disclosed in my U. S. Patent No. 2,131,147, wherein it comprises principally spring 19 and arm 10.

By effect of this rocking movement of the cop supporting frame the winding spindle 6 is rocked out of the winding position together with the full cop 8 and instead the winding spindle 6' carrying an empty cop tube 8' is rocked into this position in which it is immediately driven by the endless driving belt by frictional engagement therewith. The rocking movement of the cop supporting frame during which the cop tubes 8, 8' perform a gyrating movement is limited by the arms 1'' and 2'' of the face plates 1, 2 hitting the above-mentioned lower longitudinal rail (not shown), whereby the cop supporting frame is secured in its new position of adjustment at the same time.

Prior to the beginning of the rocking movement of the cop supporting frame the barbed needle 14 will have been ejected by cooperation of its smooth end with the abutment 16 through the semi-circular recess in the circumference of the stop disc 17. Consequently, the barbed needle 14 will bear, by action of its compression spring 15, against the stop disc 17 during the said rocking movement of the cop supporting frame, whereas the barbed needle 14' which previously had been bearing against the stop disc 17 will be moved into registration with the said recess of the stop disc 17 and is passed through this recess of the stop disc 17 by action of its compression spring 15' (Fig. 6). During this rocking movement of the carriage through 180° by which the spindle 8 is carried from winding position (Figure 1) to doffing position (Figure 6), the barbed needle 14' grips, by means of the hook thereof, the thread portion passing between the thread guide 13 to the full cop tube 8, that is, to the stop 12, which thread portion is thus laterally deflected by the barbed needle 14' in the manner shown in Fig. 6 to such an extent that the thread is moved on the path of movement

of a thread catch 19' provided on the head 7' of the winding spindle 6' so that the thread is caught by this thread catch and firmly clamped to the said head 7' by clamping action of the thread catch in order to be then wound on the empty cop tube 8'. The return movement of the frame is performed by means similar to that disclosed in my U. S. Patent No. 2,131,147 wherein it comprises particularly draw spring 19.

Due to the tension set up in the thread, owing to the winding spindle 6 carrying the full cop tube 8 continuing rotating by inherent kinetic energy, the thread is broken between the two spools 8, 8', whereby the complete winding provided with a terminal winding may be disconnected from the head 7 of the spindle. The cop supporting frame then moves again from its initial winding position (Figure 6) to a position toward the right during which motion the needle 14' is also carried toward the right and comes to bear on the abutment 16. The full cop tube 8 inserted in the driving head of the winding spindle 6 is then interchanged for an empty cop tube, whereupon the cycle of the operations explained is repeated.

In the end period of the operation for winding the cop tube 8' for effecting the terminal winding the thread guide 12' is rendered effective and during the subsequent half turn of the cop supporting frame the barbed needle 14 deflects the thread laterally so that it is caught by the thread catch 19 of the head 7 of the winding spindle 6, then moving into winding position, and is secured to said head, whereupon the thread is wound on the empty cop tube having been inserted in this head.

The hook-like thread guides 12, 12' arranged on the thread holding device 10 may be of more or less length or be adjustable in order to provide for effecting the terminal winding at a point of the cop tube as desired.

The spindle driving heads hereinafter described are provided with a clamping element which is urged against a counter surface by action of centrifugal force while the cop tube rotates, for the purpose of retaining the thread having been inserted between the clamping element and the counter surface at the time of the interchanging of cop tubes, which retaining effect endures until the cop tube stops moving.

By this means the result is obtained without any further provisions that when the completely wound, stopped cop tube is released from its mounting means it drags the thread end having been kept back at the place of clamping along so that no thread waste is retained at the place of clamping and this place is therefore free from thread waste at all times. Consequently, the completely wound cop tube is in no way prevented by the thread material, that is, thread waste, from moving out of engagement with the mounting means thereof, there being thus no risk of the cop tube getting stuck.

Figs. 9 to 12, different views of a spindle driving head are shown, which head for the purpose of fastening the same to the winding spindle 6 (Fig. 13) is provided with a bore 24 in an inner partition wall 23 thereof (Fig. 12). The hollow space 25 of the spindle driving head is provided with a holding device for the reception of cop tubes 8, 8' respectively (Figs. 12a and 13). The space 25 of the spindle driving head is provided at the respective end with an enlargement 27 in which a curved leaf spring 28 is arranged one end of which is connected to the spindle driving

head 7a by means of a screw 29 and the other end carries a weight 30 on the inner side thereof. When the spindle head is at rest, the correspondingly curved leaf spring 28 assumes a position as shown in Figs. 11 and 12. In this position, the leaf spring 28 recedes for the major part of its length toward the free end thereof from the wall enveloping the enlargement 27. This wall is provided at its front end with a recess 31 extending over a certain circumferential length, one circumferential end of which recess terminates in a slot catch 31' for the thread. A prong 32 limiting this slot towards the front end of the wall is somewhat deflected outwardly from the remainder of the wall, enveloping the space 27, as shown in Figs. 10 and 11. In Fig. 12a, which shows a cop 8 in the winding head 7a and the winding head mounted on the winding spindle 6, the spindle 6 is represented as being supported in ball bearings 50 in bearing support head 51 on face plate 1. Inside, the head 7a is provided with a spring 28 and also a holding device comprising an insert 52 of hard rubber having a conical bore for receiving the end of the cop tube. This insert 52 lies against an intermediate disc 53 of such thickness that the foot of the bobbin lies in spindle head 7a at such depth that the winding thread will lie at the proper position at the beginning of the winding operation. The disc 53 is exchangeable for discs of different thickness.

When, during the operation of the winding machine, the spindle driving head is turned in the direction indicated by the arrow in Fig. 10, the leaf spring 28 weighted at its free end swings outwardly over the full length thereof, by action of centrifugal force, onto the wall portion of the spindle driving head enveloping the space 27 all around, as shown in Fig. 10. In this way the recess 31 provided in this circumferential wall portion is bridged for a corresponding width, that is, limited at the front side, by the leaf spring 28 which, however, does not extend all the way up to the front end of the spindle driving head 7a. If thereupon the winding thread 33 is brought within the range of the spindle driving head 7a by being accordingly deflected laterally (as regards the course of the thread), so that the thread is caught by the prong 32 acting as a thread catch and is moved along the slot 31' by means of this prong, the thread then comes to lie between the leaf spring 28 and the wall of the spindle driving head where it is clamped sufficiently in order to be subsequently directed over to the empty cop tube inserted in the spindle driving head and to be wound thereon. In clamping the thread between the leaf spring 28 and the wall of the spindle driving head 7a the thread is cut by effect of the thin and thus sharp outer edge of the leaf spring 28 and is thus severed from the full cop tube.

As shown in Fig. 13, the full cop tube 8 is moved out of winding position by effect of the rocking movement of the cop supporting frame and an empty cop tube 8' is moved into this position. During effecting this operation of interchanging cop tubes the barbed needle 14', which has been accordingly controlled in automatic manner, has moved the winding thread 33 within the range of the spindle driving head 7a on the winding spindle 6'. Since this winding spindle 6' is driven in the position of the cop supporting frame shown, the winding thread arriving from the thread guide 13 is subsequently

caught by the prong 32 of the spindle driving head, whereupon the thread is severed.

After the winding spindle concerned has come to rest on the completion of the winding and the subsequent operation of interchanging cop tubes, the leaf spring 28 assumes its condition of inoperation again in which the clamping action between the leaf spring 28 and the wall of the spindle driving head 7a serving as a counter surface therefor, in an amount as required for retaining the corresponding thread portion, ceases. In consequence thereof the thread which previously had been retained by the leaf spring 28 can be pulled out of the spindle driving head without any further provisions by the full cop tube, when the latter is released from engagement with the bearing means thereof.

Therefore, the thread is not retained in the spindle driving head so that no thread waste can accumulate in the latter. This makes it possible, on the other hand, to effect a smooth delivery of the thread to the clamping point of the spindle head and a more secure attachment and of securely clamping threads of any size varying between the thickest and thinnest threads.

In the example shown in Figs. 14 to 16, into an outer circumferential groove 40 of the spindle driving head 7b is inserted an open ended ring 41 which is provided at one end with a projecting arm 42 serving as a thread catch. As evident from Figs. 15 and 16, the portion of the ring 41 adjacent the end thereof which forms the thread catch bears closely against the spindle driving head for a distance of over half the circumferential length, whereas concerning the remaining portion of the circumference of the ring 41, clearance is provided between the ring and the spindle driving head 7b, in consequence whereof it is evident that the bearing of the ring 41 against the spindle driving head 7b is non-uniform to a corresponding extent. This unequal bearing engagement between the ring 41 and the spindle driving head 7b is maintained due to a consequent weight distribution of the ring 41 by action of centrifugal force, when the spindle driving head rotates, so that as the winding thread is caught by the catch arm 42 of the ring 41 it is clamped between the ring 41 and the spindle driving head, whereupon the operation of severing the thread arriving from the full cop tube takes place.

After the spindle driving head has come to rest, on the completion of the winding and the subsequent operation of interchanging cop tubes, and thus stops turning, the ring 41 is urged against the spindle driving head 7b merely by action of its own weight and thus no longer with considerable force, so that the thread which is then retained by the ring only slightly can easily be pulled off the spindle driving head 7b.

In the examples hereinafter described by taking reference to Figs. 17 to 23, the spindle driving head is provided with a rigid clamping element which during the operation of the winding machine is moved by action of centrifugal force from inside to outside, due to being correspondingly arranged, whereby it is urged against the counter surface.

By this means, the result is obtained that with the aid of simple, altogether unsusceptible means which warrant a reliable operation in the long run the thread can be temporarily retained.

In the example shown in Figs. 17 to 19, in the enlargement 27 of the spindle driving head 7c a rigid arcuate wing 43 is pivotally mounted by

means of a threaded stud 44. When the spindle head does not rotate, the wing 43 assumes, for example, a position as shown in Fig. 19. In this position the wing 43 bears with its reduced end adjacent the threaded stud 44 against the circumferential wall limiting the enlargement 27, whereas the remaining part of the wing recedes over its full length inwardly away from the said circumferential wall.

As the winding spindle provided with the spindle driving head is rotated in the direction of the arrow indicated in Fig. 18, the wing 43 swings by action of centrifugal force from inside to outside, so that it bears against the inside of said circumferential wall over the major part of its length, as indicated in Fig. 18. In this way the recess 31 provided in the circumferential wall is bridged, that is, limited at the front end by the wing 43 for the width of the same. If then the winding thread 33 is so moved within the range of the spindle driving head 7c by being accordingly deflected by means of the barbed needle 14 that it is grasped by the prong 32 serving as a thread catch and is moved by the latter along the slot 31', the thread then comes to lie between the wing 43 and the wall of the spindle driving head. In this position the thread is clamped fast enough so that it is automatically torn between the spindle driving head and the still rotating full cop tube, as previously described.

After the winding spindle has come to rest on the completion of the winding and the subsequent operation of interchanging cop tubes, the wing 43 which is then influenced merely by its own weight is in no position of rotation of the spindle driving head urged against the counter surface presented to the ring by said head with sufficient pressure for exerting the necessary clamping effect for retaining the thread between the wing 43 and the said counter surface.

In the example shown in Figs. 20 to 23, in the enlargement 27 of the spindle driving head 7d a bi-partite ring 45, 46 is arranged, so that the ring portion 45 is fixed to the spindle head 7d, whereas the ring portion 46 is loosely inserted therein. The two ring portions 45, 46 are formed from an initially closed ring of a diameter corresponding to that of the enlargement 27. This ring has then been subdivided by oblique slots 47 of such width that the two ring portions 45, 46, when joined together so that their oblique end surfaces bear on each other, come short of the diameter of the original ring, that is, the enlargement 27 inside the spindle driving head 7d by an amount which corresponds to the radial clearance of the loose ring portion 46 within the enlargement 27. The two ring portions 45, 46, are arranged in the spindle driving head 7d in regard to their oblique end faces in such manner that the fixed ring portion 45 prevents the ring portion 46 loosely inserted in the spindle driving head 7d from dropping out of the spindle driving head in the axial direction.

When the winding spindle provided with the spindle driving head begins to rotate, the ring portion 46 loosely inserted in the spindle driving head is moved from inside to outside by action of centrifugal force so that it comes to bear on the inner circumferential surface of the enlargement 27 which serves as a counter surface for this portion, as shown in Fig. 21. Thereupon, the winding thread is introduced in the slot 31' between the ring portion 46 and the prong 32, that is, the wall of the spindle driving head 7d, during the operation of interchanging cop tubes.

at the winding position, and is clamped fast between these parts. In the condition of rest of the winding spindle, the ring portion 46 is influenced merely by action of its own weight, so that it is urged against the counter surface presented to it by the spindle driving head in no position of rotation of the latter with an amount of pressure sufficing for exerting the required clamping effect for firmly retaining the thread. The thread is finally pulled out of the spindle driving head by the completely wound cop tube being released.

Instead of a ring portion fixed to the spindle driving head, other kinds of stop means may be provided on the spindle driving head for the loose ring portion acting as a clamping element, so as to limit the movement of the last named ring portion in the radial and axial direction of the cop tube.

I claim:

1. In a thread transfer mechanism for cop winding machines having a slidable, rockable carriage, a plurality of spindles mounted in said carriage, a thread catch on each spindle, a barbed needle adjacent each spindle mounted longitudinally slidably in said carriage, a thread hook adjacent an end of each bobbin mounted on the carriage for retaining the thread during movement of a full bobbin from winding to non-winding position during a rocking movement of the carriage, and means for moving the barbed needle corresponding to a spindle having a full bobbin to transfer the thread to the catch of a spindle having an empty bobbin.

2. In a thread transfer mechanism for cop winding machines, a rockable, slidable spindle carriage, a plurality of spindles mounted in said carriage, each of said spindles having a bobbin-retaining head and each having a thread catch adjacent its head, a hook on said carriage adjacent the last portion of each bobbin to be wound, a barbed needle adjacent each spindle and bobbin, means for moving said needles to transfer the thread being fed from a full bobbin, after rocking of the carriage, to the thread catch of a spindle having an empty bobbin, while the thread hook adjacent the end of the full bobbin retains the thread in line with the last end of said full bobbin to be wound during said transfer.

3. In a thread transfer mechanism for cop winding machines having a slidable, rockable carriage, a plurality of spindles mounted in said frame carriage, each spindle having a bobbin-retaining head at one end, and each having a thread catch at said end, a plurality of counter bobbin holders mounted on said carriage at positions opposite the spindle heads, a guide hook adjacent each counter holder, barbed needles mounted in said carriage adjacent said spindles, a coil spring on each needle, an abutment for the ends of said needles, a stop for the ends of said needles, said needles successively cooperating with said abutment and stop according to the longitudinal and rocking positions of the carriage, the ends of said needles engaging said abutment during winding operations and during the greater part of the rocking movements until the end of the rocking movements when the end of a needle passes out of alignment with the abutment and under the influence of the spring moving longitudinally into engagement with said stop, and during said longitudinal move-

ment the barbed needle transferring the thread to the thread catch of a spindle having an empty bobbin.

4. In a thread transfer mechanism for cop winding machines having a slidable, rockable carriage, a plurality of spindles mounted in said carriage, a thread catch on each spindle, a clamping device on each spindle adjacent the thread catches thereof, said clamping device comprising a resilient jaw having a weight responsive to centrifugal force and an opposed clamping surface, said clamping device acting to hold the thread during rotation of the spindle and release the thread when the spindle ceases to rotate, a barbed needle adjacent each spindle mounted longitudinally slidably in said carriage, a thread hook adjacent an end of each bobbin mounted on the carriage for retaining the thread during movement of a full bobbin from winding to non-winding position during a rocking movement of the carriage, and means for moving the barbed needle corresponding to a spindle having a full bobbin to transfer the thread to the catch of a spindle having an empty bobbin.

5. In a thread transfer mechanism for cop winding machines having a slidable, rockable carriage, a plurality of spindles mounted in said carriage, a thread catch on each spindle, a clamping device on each spindle adjacent the thread catches thereof, said clamping device comprising a resilient leaf spring having one end secured to the spindle and having a weight mounted thereon responsive to centrifugal force and an opposed clamping surface, said clamping device acting to hold the thread during rotation of the spindle and release the thread when the spindle ceases to rotate, a barbed needle adjacent each spindle mounted longitudinally slidably in said carriage, a thread hook adjacent an end of each bobbin mounted on the carriage for retaining the thread during movement of a full bobbin from winding to non-winding position during a rocking movement of the carriage, and means for moving the barbed needle corresponding to a spindle having a full bobbin to transfer the thread to the catch of a spindle having an empty bobbin.

6. In a thread transfer mechanism for cop winding machines having a slidable, rockable carriage, a plurality of spindles mounted in said carriage, said spindles having heads each provided with a bobbin-receiving socket and with a wide slot, a thread catch on said head adjacent said slot, a leaf spring in said socket having a weight and comprising one jaw of a clamp, a counter clamping jaw against which the spring is pressed by centrifugal force when its spindle is rotating and from which it withdraws when not rotating, a barbed needle adjacent each spindle mounted longitudinally slidably in said carriage, a thread hook adjacent an end of each bobbin mounted on the carriage for retaining the thread during movement of a full bobbin from winding to non-winding position during a rocking movement of the carriage, and means for moving the barbed needle corresponding to a spindle having a full bobbin to transfer the thread to the catch of a spindle having an empty bobbin.

7. A thread transfer device as defined in claim 4 and in which the resilient jaw comprises an open ring movable radially with respect to the spindle.

WALTER SIEGENTHALER.
